(57) **CLAIM**

The ornamental design for an open-ended ratchet wrench, as shown and described.

DESCRIPTION

FIG. 1 is a perspective view of an open-ended ratchet wrench showing my new design;

FIG. 2 is a top plan view thereof;

FIG. 3 is a left side elevational view thereof, the opposite side being the same in appearance;

FIG. 4 is a bottom plan view thereof; and,

FIG. 5 is a front elevational view thereof with the open-ended ratchet wrench inverted.
